WEATHER SHIELD FOR A VEHICLE WINDOW

Laurence B. Tipper, Toronto, Ontario, Canada
(1216 York Mills Road, Don Mills, Ontario, Canada)

Filed Aug. 3, 1962, Ser. No. 71,174

Term of patent 7 years

(Cl. D14—6)

FIG. 1 is a perspective view of a weather shield for a vehicle window opening showing my new design;
FIG. 2 is a side elevation of FIG. 1;
FIG. 3 is a front elevation of FIG. 1;
FIG. 4 is a bottom plan view of FIG. 1;
FIGS. 5 and 6 are sections taken respectively on lines 5—5 and 6—6 of FIG. 1.

I claim:

The ornamental design of a weather shield for a vehicle window, as shown.
